CLAIM

The ornamental design for a swivel head make up brush, as shown and described.

DESCRIPTION

FIG. 1 is a front perspective view embodying the inventive swivel head make up brush showing only one brush swiveled upward for use;

FIG. 2 is a right side view of the device as seen in FIG. 1;
FIG. 3 is a left side view of the device as seen in FIG. 1;
FIG. 4 is a front view of the device as seen in FIG. 1;
FIG. 5 is a rear view of the device as seen in FIG. 1;
FIG. 6 is a top view of the device as seen in FIG. 1;
FIG. 7 is a bottom view of the device as seen in FIG. 1;
FIG. 8 is a front perspective view of the device seen in FIG.

1 showing both brushes swiveled outward;

FIG. 9 is a right side view of the device as seen in FIG. 8;
FIG. 10 is a left side view of the device as seen in FIG. 8;
FIG. 11 is a front view of the device as seen in FIG. 8;
FIG. 12 is a rear view of the device as seen in FIG. 8;
FIG. 13 is a top view of the device as seen in FIG. 8; and,
FIG. 14 is a bottom view of the device as seen in FIG. 8.
The broken lines in the figures depict environmental subject matter only and form no part of the claimed design.
